[57] ABSTRACT

A device comprising: an elongated handle; a coil spring having an inner diameter large enough to receive a golf ball, said spring being secured to the handle in such manner that the axis of the spring extends at right angles to the direction of elongation of the handle; and clip means secured to the periphery of the spring and having an extension which is flexible and extends inwardly towards the axis of the spring to engage and hold the ball in the spring once the ball is disposed in the spring.

FIG. 8

GOLF BALL PICKUP DEVICE**FIELD OF THE INVENTION**

My invention is directed toward a device which enables a golfer or another to pick up a golf ball lying on the ground without bending or stooping.

SUMMARY

To this end, I employ an elongated handle having a coil spring secured to one end. The inner diameter of the spring is large enough to receive a golf ball and the axis of the spring is disposed at right angles to the direction of elongation of the handle. Clip means secured to the periphery of the spring is provided with an extension which is flexible and which extends inwardly towards the axis of the spring to engage and hold the ball in the spring once the ball is disposed in the spring.

Thus the user grasps the handle and drops the spring around the ball. The clip means holds the ball in position. The user then moves the handle until the spring is disposed in hand whereby the ball can be removed by hand.

BRIEF DESCRIPTION OF THE DRAWINGS

In the drawings:

FIG. 1 is a perspective of my invention in use;

FIG. 2 is a detail thereof;

FIG. 3 is a top plan of one spring clip used in my invention;

FIG. 4 is a front elevation of the clip of FIG. 3;

FIG. 5 is a side elevation of the clip of FIG. 3;

FIG. 6 is a top plan of another clip used in my invention;

FIG. 7 is a front elevation of the clip of FIG. 6; and

FIG. 8 is a side elevation of the clip of FIG. 6.

DETAILED DESCRIPTION OF PREFERRED EMBODIMENTS

Referring now to FIGS. 1-8, an elongated handle 10 which can be telescopically collapsible receives in a bore in one end an extended end of coil spring 12.

45

50

55

60

65

Spring 12 has three turns and has an inner diameter large enough to accommodate a golf ball 14. The axis of the spring is disposed at right angles to the handle.

A spring clip has two vertical arms 16 which are spaced apart and essentially parallel. Each arm has two spaced U type clips 18 or ring shaped loops 20 which engage the top and adjacent loops respectively of the spring.

The top ends of each of the arms 16 are secured by corresponding horizontal extensions 22 to a horizontal ring 24 disposed inwardly toward the axis of the spring and positioned above and intermediate the vertical arms.

When the ball is disposed in the spring, the ring 24 snaps onto the ball and holds it in position for use as previously described.

While I have described my invention with particular reference to the drawings, such is not to be considered as limiting its actual scope.

Having thus described this invention, what is asserted as new is:

1. A device which can be used to pick up a golf ball comprising:

25 an elongated handle;
a coil spring having an internal diameter large enough to receive a golf ball, said spring being secured to the handle in such manner that the axis of the spring extends at right angles to the direction of elongation of the handle; and

clip means secured to the periphery of the spring and having an extension which is flexible and extends inwardly towards the axis of the spring to engage and hold said ball in the spring once the ball is disposed in the spring;

wherein said means engages an outermost loop of the spring and a loop next to the outer loop; and
wherein said extension includes a ring lying in a plane parallel to the plane of the outermost loop.

2. The device of claim 1 wherein said means engages each of said loops in two position and said ring is secured to the body of the means by two oppositely disposed arms.
